KINETIC PROJECTOR

Cletus L. Luebbe, Fort Totten, Long Island, N. Y.

Application January 19, 1939, Serial No. 251,747

19 Claims. (Cl. 242—54)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a kinetic projector for the controlled projection to a distance of wire, cable, line, hose, tubing, rods, ribbon, rope and other shapes, forms and kinds of materials by imparting sufficient kinetic energy to the material to propel it the desired distance.

One of the main objects of the invention is to provide means for drawing wire, cable, or other material of the character indicated from one or more reels, coils, piles or bundles and feeding the same to a system of projection rollers on which sufficient velocity is imparted to the wire or material to propel it to the desired distance.

In the process of laying wire from either a moving or a stationary vehicle or conveyance, the conventional method has been to draw the wire from a reel, coil or pile in such manner as to necessitate the manual removal of the same from the path traversed by the vehicle. Also, the conventional method requires the manual drawing of wire from a reel to provide slack for looping wire over bushes and about obstructions. Obviously, such a procedure is slow and laborious. According to my invention, the wire is projected either from a moving or a stationary vehicle or conveyance at any desired angle of elevation or depression, and at any desired horizontal angle to distances required; while at the same time automatically providing slack or spare wire for draping wire on or about bushes, trees or other obstructions.

Another main object of the invention is to provide means coordinated with the planetary roller system for varying either or both the vertical angle and the horizontal angle of discharge, for the purpose of elevating or depressing the trajectory and for the purpose of controlling the horizontal direction of discharge of the wire or other material with respect to the ground; or with respect to the conveyance upon which the invention is mounted or installed.

Another main object of the invention is to provide means by which wire or other material may be projected to a distance, either vertically, horizontally or at other angles, from a moving vehicle or conveyance or from a vehicle at rest; and an important object is to provide means for controlling the distance to which the material is projected.

Another object of the invention is to provide means by which wire or other material may be

projected to a distance from a moving vehicle or conveyance at a rate which may be controlled for the purpose of providing a desired amount of slack or spare lengths of material.

5 A further object is to provide means for guiding the wire or other material so that it will not run off of the rollers, pulleys, wheels, or other rotary devices; also to provide a guide or guides that will permit the insertion of or removal of the wire from between the rollers or other rotary driving devices without the necessity of cutting the material, and without the necessity of withdrawing or inserting ends of the material.

15 Another object is to provide a framework for holding guide supports, guides, rollers, axles, springs and bearings in proper position with reference to each other; and also to provide a means for quickly opening the framework for the removal of wire or other material and for the removal and replacement of rollers, pulleys, wheels, or other parts.

Another object is to provide a means for automatically maintaining rollers, pulleys, wheels, or rotary driving devices in contact with the material with sufficient pressure for the purpose; and further to provide means for automatically adjusting rollers, pulleys, or other rotary driving devices to allow for varying thickness of the material which is to pass between the rollers.

25 30 Another object of the invention is to provide means for adjusting the framework and for locking the framework at any desired angle of elevation; and also to provide means for adjusting the framework and for locking the framework in any desired angle of azimuth or horizontal angle.

Another object of the invention is to provide means for guiding the material between the rollers in a reverse direction when desired; also to provide a reversing guide which permits the removal or insertion of the material between the rollers without the necessity of cutting the same or without being obliged to insert or remove ends of the material.

40 45 Another object of the invention is to provide means for guiding the wire or cable in a manner that will avoid injury to the same; and to provide means including auxiliary guides for reducing friction, wear or possible damage to the material entering the centering guide.

Another object of the invention is to permit the use of any suitable source of variable power for driving the mechanism to project the material to varying distances away from or onto a particular point by varying the rate of discharge, verti-

cal angle of discharge and/or horizontal angle of discharge.

Another object of the invention is to provide an automatic brake to prevent over-spinning of reels and to govern the action of said brake by means of a dash pot.

Other objects, applications and advantages are within the scope of the invention and will appear as the description proceeds.

The invention will now be described in detail with reference to the accompanying drawings, in which:

Fig. 1 is an elevation showing a preferred embodiment of the invention comprising a roller and gear system, showing a rotatable supply reel, 15 braking and cable control means and guide elements;

Fig. 2 is a plan view of the embodiment shown in Fig. 1;

Fig. 3 is an end section taken on line 3—3 of Fig. 2 showing the roller system and gearing 20 flexibly connected to a prime mover such as an electric motor;

Fig. 4 is a diagrammatic view of one embodiment of planetary roller system for projecting wire and showing trajectories thereof;

Fig. 5 is a diagrammatic view of another embodiment of the planetary roller system and featuring means for trajectory control in a vertical plane;

Fig. 6 is an end view of auxiliary guide rollers;

Fig. 7 is a side view, partly in section, showing intermediate guide elements and auxiliary guide rollers in relation to the projection rollers;

Fig. 8 is a front view looking into the leading 35 end of the swivelled guide element shown in Fig. 1;

Fig. 9 shows in perspective a simplified form of the invention with the roller system coupled to a power unit;

Fig. 10 is a view, partly in section, showing the system of projection rollers coupled flexibly to a prime mover; and

Fig. 11 is a sectional view of the locking means taken on the line 11—11 of Fig. 10.

The theory employed in projecting wire cable or other material to a distance is to impart sufficient kinetic energy to the same by means of my roller system, to do the work of propelling it. Means is provided for elevating, depressing or otherwise controlling the trajectory, and it will be seen that the distances to which wire may be projected, or the height to which it may be projected, are simply functions of elevation, velocity and ballistic characteristics of the material. Means is also provided for rotating the projector horizontally and hence directing the wire to any desired angle. By varying the rate of discharge, slack or spare wire is provided as conditions require. In the devices that have been constructed to date, I have found that a roller speed of about 3600 R. P. M. and a wire speed of about 4100 feet per minute will project W-110 field telephone wire to a distance of about 135 feet, the highest point of the trajectory being, in this case, about 40 feet.

Referring to the drawings, numerals 1 and 2 designate the projection rollers, which are normally maintained with their peripheral surfaces in yieldable frictional contact and between which the wire, cable or other material denoted by 5 is fed. It has been found that for projection of wire, cable and the like, a soft rubber or other yieldable surface coating for these projection rollers is desirable as shown at 1c and 2c of Fig. 3. 75

Roller 1 is mounted for rotation on axle 3 and roller 2 is mounted on axle 4. As will be seen by reference to Figs. 1, 3, 5 and 9, a third roller 6 functions as a drive roller in certain embodiments of the invention. Said roller is keyed on axle 10. The roller system is operatively mounted in a framework generally designated by numeral 7, and for purposes of operation, it will be seen that said framework may be regarded as being formed in sectional components, which components are adjustable in relation to one another both in vertical and horizontal planes to vary and control the trajectory as well as direction in azimuth or a horizontal plane of the projected material.

As seen in Figs. 1, 3 and 9, roller 1 is journalled in bearings as at 8a and roller 2 in bearings 8 which are free to move in guides formed in frame 7 and are, therefore, self-adjusting under tension of springs 9 to maintain roller 2 under proper pressure and in yieldable frictional contact with roller 1 in order to permit sufficient movement to grip the cable or other material during the operation of projection, while compensating for inequalities and differences in size and thickness of the material being projected.

To permit access to working parts carried by frame 7 for purposes of adjustment and replacement, said frame is formed in separate parts hinged as at 14 and normally held closed by a suitable fastener as at 11. Thus it will be seen that the framework may be readily opened for the purpose of replacing and adjusting rollers, for inserting wire between the projection rollers 1 and 2, also for removing the wire or cable without the necessity of cutting the same or removing ends. The frame 7 is pivoted to rotate in a vertical plane about an axis which coincides with the axis of shaft 10 for the purpose of varying and controlling the trajectory. In the embodiments shown in Figs. 1, 3 and 9, means is provided to maintain the frame in different adjusted positions comprising a slotted quadrant 12 and a locking device 13 cooperating therewith.

Referring more particularly to Figs. 1 and 3, it will be noted that the framework is also adjustable in a horizontal plane to control the direction of discharge of the projected material in azimuth. As previously explained, upper frame 7 is rotatable in a vertical plane about shaft 10 as an axis. For the purpose of effecting an adjustment in azimuth, the base frame proper denoted by 17 of the upper frame structure is formed with a peripheral flange portion 17b, which is adapted to be supported for rotatable movement on a corresponding flange 16b formed around the upper edge of sub-base frame 16, the last-named flange acting as a slide-way for rotation of the upper frame structure in azimuth.

A system of bevel gearing functions to transmit drive to the roller system. Mounted in frame 16 are bearings 17a in which drive shaft 18a is journalled. Bevel gear 18 is keyed to said shaft 18a, and this gear meshes with gear 19, which is keyed to shaft 19a, said shaft also carrying bevel gear 20. Gears 19 and 20 are oppositely disposed, one interiorly of the sub-base frame 16 and the other interiorly of base-frame proper 17 on common connecting shaft 19a which is journalled in bearings 19b. The rotatable adjustment in azimuth of base frame 17 relative to sub-base frame 16 is made about connecting shaft 19a as an axis. Meshing with upper gear 20, another gear 21 is provided which is keyed to roller drive shaft 10, which shaft in turn is keyed to drive roller 6. Shaft 10 is disposed horizontally and is jour-

nalled in bearings 21a, 21b and 21c. It will be noted that in effecting adjustment to control trajectory, frame 7 is rotatable about shaft 10 as an axis, and as previously described, frame 7 may be held in adjusted positions by means of locking device 18 cooperating with slotted quadrant 12.

In effecting the adjustment in azimuth, base frame 17 may be rotated in a horizontal plane in relation to sub-base 16 and about connecting shaft 19a as an axis. This rotational movement in a horizontal plane is made possible by means of cooperating flange portions 16b and 17b, above described, which are slidably related and have their cooperating surfaces properly machined for that purpose. For the purpose of locking the frame 17 in adjusted positions in azimuth, the flange 17b has a slot 41 formed therein, said slot permitting a movement in arc of nearly 360°. Locking lever 15, threaded into the flange 16b as at 42, is provided to maintain the frame 17 in adjusted positions. From the foregoing it will be apparent that both the vertical and horizontal angles of discharge may be controlled. It will also be understood that any suitable source of variable speed power may be utilized; also, that any suitable prime mover coupled with a flexible transmission system may be adapted to the use of this projector. A prime mover M is indicated in the drawings and this may be an electric motor, internal combustion engine, or motor-generator unit. A flexible coupling between the prime mover M and the projecting mechanism is generally denoted in the drawings by numeral 43. Additional flexibility is provided by a flexible shaft 69.

As will be seen by reference to Figs. 1 and 2, a brake mechanism is provided which functions to effect automatic control of the projecting operation and to prevent over-spinning of the supply reel. From a supply reel 22 wire or cable denoted by 5 is fed to projection rollers 1 and 2. The brake comprises a brake bar 24, pivotally secured at its end by means of a stud 23 to a strut 64a of the reel-supporting framework. Brake lining 25 is interposed between the bar 24 and flange 44 of supply reel 22, said lining being maintained in braking contact by brake actuating spring 26. This spring is attached at one end to bar 24 and at its opposite end to the reel support by bracket 45, and normally functions to maintain said brake lining in braking contact with the reel. Interposed between supply reel 22 and the projector mechanism and forming part of the brake control mechanism is arm 28, which is operatively coordinated with the brake bar 24 by means of shaft 46, journalled in bearings 47 and 48. Crank arm 49 is keyed to shaft 46 and is provided with crank-pin 50 which is in operative engagement with a slotted member 51 attached to brake bar 24. Journalled at the end of arm 28 is a grooved carrier wheel 29 on which wire or cable 5 rides while being fed from the supply reel 22. Swivelled on the shaft of said wheel is a tubular guide 33 having its leading edge flared and through which the cable 5 is centered and guided in its travel from reel to projector. This guide 33 is formed so that its top portion may be opened on hinge 33a by releasing fastener 33b to facilitate removal of the cable and whereby the cable may be threaded into position without cutting. See Fig. 8. The arm 28 occupies a position intermediate of supply reel 22 and it will be noted that said arm is swivelled as at 52 to turn on its longitudinal axis so that guide element 33 may also turn or swing on the same axis to follow the side-to-side swing

of the cable 5 as it is unwound from the supply reel 22. Thus, the guide element 33 functions both to center and guide cable 5 in its travel from reel to projector. As shown in Fig. 1 in full lines, 5 arm 28 is in normal position with the reel at rest, brake bar 24 being raised by spring 26 so that the brake lining is in contact with the reel and applying a braking force to said reel. More or less tension is exerted upon the cable 5, which is in position 10 between projection rollers 1 and 2 in readiness for the operation of projection. When a force is applied to cable 5 by rollers 1 and 2, this force is transmitted through carrier-wheel 29, arm 28 and bar 24 to act on spring 26. Normally 15 spring 26 raises bar 24 and applies a braking force to the reel through brake lining 25, but a downward motion of bar 24 releases the braking force. Thus, it will be apparent that when a projecting force is applied to cable 5 by rollers 1 and 2 in a 20 direction indicated by arrows, as seen in Figs. 4 and 5, through the action of arm 28 which responds to the cable movement, the brake is released, permitting reel 22 to revolve freely to pay out the cable. As the force of projection is expended, the arm 28 tends to return gradually to 25 its normal position whereby the braking action is also gradually applied through the tension of spring 26. It will be understood that arm 28, carrier wheel 29 and guide element 33 take up various positions as the arm 28 moves in a vertical plane in response to the force of projection exerted upon cable 5, and through shaft 46 and crank arm 49 corresponding control force is transmitted to the brake bar 24 which is substantially proportionate to the energy of projection. One position of the arm 28 and parts carried thereby is shown in dotted lines in Fig. 1, where in shifted position arm 28 is denoted by 28a, brake bar as 24a, carrier wheel as 29a, guide element as 33a, and cable as 5a. To overcome 30 the objection of a jerky braking action, caused by the oscillating or hunting movement of arm 28, a dashpot 27 serves to smooth out the movement both of arm 28 and brake bar 24 whereby a 35 smooth braking action is produced.

Referring to Fig. 1, the supply reel 22 is mounted in a skeleton frame generally designated as 64 and pedestals are provided as at 65 to support the bearings 47 and 48 in which shaft 46 is journalled. The frame work 64 and pedestals 65 are bolted to base 66. The roller system and gearing mechanism are mounted in a supporting skeleton frame work as at 67. It will be understood that the apparatus is primarily intended for portable use and generally will be installed in a truck, the bed of the truck being denoted by reference character 68 in Fig. 1.

Referring to Figs. 1 and 2, 6 and 7, a system of auxiliary feed and guide rollers are shown. One arrangement comprises rollers 34, 35, 36 and 37; and shafts for these rollers are denoted by 30a, 35a, 36a and 37a, respectively. These rollers are arranged to form an auxiliary guide system for reducing friction between the wire or cable and the guide proper denoted by 33. A centering guide element 38 is used in some instances, which guide takes the form seen in Fig. 7. When projection rollers 1 and 2 are of sufficient width, the centering guide 38 may be eliminated, and the auxiliary guide rollers alone will be sufficient to guide the wire between rollers 1 and 2. Referring again to Fig. 1, it will be apparent that tension is required on wire 5 to properly control the braking action and release the supply reel. Also to set the reel in motion and to maintain this mo-

tion, proper tension on the wire or cable is required. When rollers 1 and 2 are slowed down, the spring 26 functions to actuate the brake and thus to put tension on the wire. It follows that there will always be tension more or less on the wire or cable which will keep the same in contact with the auxiliary guide rollers in such manner as to avoid entanglement with the roller system. A pair of retracting rollers are indicated by numerals 39 and 40. These rollers are disposed vertically and are used when rewinding wire to prevent the wire from shifting laterally and slipping off rollers 1 and 2. It is intended that any suitable means for supporting auxiliary rollers 34, 35, 36, and 37, also centering guide 38, and retracting guides 39 and 40 may be utilized. By arranging the auxiliary guide supports in two sections, the parts will be made accessible for insertion and removal of wire without cutting and withdrawing ends. The auxiliary rollers just described are idlers and are so mounted as to reduce friction to a minimum.

In the embodiment shown in Fig. 10, a pair of projection rollers are employed such as 1 and 2, in which 1 is the friction drive roller and 2 the driven roller. The framework for supporting the roller system comprises base frame 16, side members 1a and 1b, and a removable top member 53. To permit removal and replacement of parts, and for the purpose of inserting and withdrawing wire or cable, latches 11a and 11b are provided whereby the top member 53 may be opened at either or both ends. Accessibility to working parts is facilitated by mounting the side member on hinge 54 whereby the side member may be swung open by releasing latch 11b and raising the top member, a lever 55 being attached to the top member for manipulating the same. It will be noted that drive roller 1 is keyed to stub shaft 10a, which shaft is journaled in bearing 56. Driven roller 2 rotates on shaft 4 which is supported in bearing blocks 57, these blocks being maintained under tension by springs 9. Said roller 2 is centered between spacing collars 58. For the purpose of controlling trajectory, the framework is pivoted for rotation in a vertical plane on the shaft 10a of roller 1 as an axis. The lever 55 is manipulated by the operator to effect the operation of trajectory control. As in other cases, means is provided for locking the frame in various adjusted positions of angular elevation, said means including screw lock 59 and lever 60. For the purpose of controlling direction in a horizontal plane, means is provided to permit adjustment in azimuth through an arc of 360°, which means comprises a turret support 61. Clamping collar 62, which may be locked and unlocked at any point by lever 63, which lever also may be manipulated to swing the entire frame structure about the vertical axis of said turret. It will be understood that when it is desired to rotate the frame structure in azimuth through an arc of more than 180°, the wire or cable being fed between rollers 1 and 2 may be readily removed after stopping the feeding operation, by opening the frame in the manner previously described and then reinserted in feeding position between the rollers, whereupon the feeding operation may be resumed. This would avoid snarling or looping of the cable about the framework. As in the case of other forms of the invention, drive shaft 10a is operatively coupled to prime mover M by flexible coupling 43.

As may be seen by reference to Figs. 4 and 5, trajectory may be controlled by rotating the roll-

er system about the shaft of one of the rollers as an axis. In the two roller system shown in Fig. 4, rollers 1 and 2 being the projection rollers, the driven roller 2 may be rotated on the axis of drive roller 1 through an arc of 90° to position 2a to produce an elevated trajectory as denoted by 5a. In a normal position, with rollers 1 and 2 as shown in full lines, the trajectory will take the form indicated by the cable 5 in full line position. A depressed trajectory may be produced by rotating roller 2 in a clockwise direction until said roller takes the position 2b.

Similarly, as shown in Fig. 5, a three roller system is shown in which 1 and 2 denote the projection rollers, while 6 represents the drive roller. Here, trajectory is controlled by rotating rollers 1 and 2 in a vertical plane about the axis of shaft 10. When rollers take the position represented by dotted lines as denoted by 1a and 2a, the trajectory is substantially vertical as indicated by 5a. The trajectory of cable 5 may thus be controlled by the adjustment indicated, and will vary according to the kinetic energy imparted to the wire or cable, being governed also by the force of gravity, the ballistic nature of the material as well as other internal and external forces acting on the wire. From a further study of these and other figures of the drawings, it will appear that both height and distance to which material may be projected may be controlled by varying either or both the angle of elevation of discharge and the rate or velocity of discharge.

As to the cycle of operation, a typical case of projecting field telephone wire may be assumed by way of example. It will be noted that throughout the description and claims the words wire and cable have been used synonymously. It will be understood, as previously stated, that a mechanism embodying the principles of the invention is applicable to a wide range of materials. As has also been pointed out, different prime movers may be used such as forms of internal combustion engines, a gasoline-electric power plant, or an electric motor alone. When using a gasoline engine, a gear and clutch system may be used similar to the power plant of an automobile. However, when an electric motor is used, speed may be regulated by a conventional rheostat control and a clutch would not be required. As will be understood, a flexible means of transmission and coupling of the power plant to the projector mechanism is contemplated and generally indicated by the disclosure.

In carrying through the cycle of operation, thread the ends of the wire from the supply reel 22 through the guide element 33, over grooved carrier wheel 29, which is coordinated with the brake, thence through the intermediate guide rollers 34, 35, 36, and 37, guide element 38, between projection rollers 1 and 2 and rollers 39 and 40. Meanwhile, the power plant has been started and first operated at a low rate of speed. The speed is accelerated and power communicated to the projector system. The amount of acceleration would depend upon the distance the wire was to be projected. As the force of projection is exerted upon the wire by the projection rollers, the brake responding automatically to the pull on the wire is released to permit the wire to be payed out by the supply reel. It will be understood that appreciable time is required to overcome inertia of the reel and body of wire which it carries, and other retarding forces must be taken into account by the operator, who makes

all necessary adjustments and regulates operational steps accordingly to compensate for the conditions met in laying wire. The horizontal and vertical angles of discharge must be varied to control direction and trajectory during various stages of the operation, all of which requires exercise of judgment and discretion on the part of the operator. To bring the projector and reel to a stop, the motor or engine is slowed down, and as the force of projection exerted on the wire is expended, the brake system operates to bring the reel to a stop.

Changes, modifications and equivalent arrangements are contemplated within the scope of the invention, as defined by the appended claims.

I claim:

1. In a mechanism for projecting cable and the like to a distance, a system of rollers having their peripheral surfaces normally held in yieldable contact, said system including a pair of projection rollers and a drive roller; means for maintaining the projection rollers under spring tension; a sectional frame in which said system is operatively mounted; means for angularly adjusting both of said projection rollers independently of the drive roller to determine and control the vertical angle of projection; said last-named means comprising an angularly adjustable carriage pivoted to said sectional frame about the axis of rotation of said drive roller; a prime mover; and means including a transmission system for operatively coupling the drive roller to said prime mover.

2. In a mechanism for projecting cable and the like, a system of rollers comprising projection rollers and a drive roller; tensioning means for normally maintaining the rollers with their peripheral surfaces in yielding frictional contact; a frame formed in sections wherein said rollers are mounted, one of said sections carrying the projection rollers; and means for adjusting said last-named section about the axis of the drive roller and independently of said drive roller to control the trajectory angle of said projection rollers; a prime mover; and means including a flexible transmission for operatively coupling the drive roller to said prime mover.

3. In a projector for wire cable, a system of rollers comprising a pair of driven rollers between which the cable is fed for projection; high speed drive means for driving the said rollers including a driving roller and a transmission flexibly coupled to said last named roller; a frame assembly in which the rollers are mounted; said frame assembly including means operable to move the same to various angular adjusted positions to thereby determine the direction of travel of the cable as it leaves said driven rollers; means carried by the frame for maintaining the driven rollers under spring tension; and means for locking the frame in adjusted positions to control the trajectory of the cable during the projecting operation.

4. In a mechanism for projecting cable and the like, a system of rollers including driven rollers between which the cable is fed for projection; tensioning means for maintaining said rollers with their peripheral surfaces in yieldable contact; means including gearing for communicating drive to the roller system; a frame assembly comprising sectional components, one of said components having the driven rollers mounted therein and being angularly adjustable in a vertical plane and another of said com-

ponents having elements of the gearing mounted therein and being adjustable in a horizontal plane; means for locking the first-named component and driven rollers in different positions to control the trajectory; means for locking the second-named component and driven rollers in different position to control the direction; a prime mover; and means including a flexible transmission system for operatively coupling the gearing to said prime mover.

5. A mechanism for projecting cable and the like to a distance comprising a plurality of projection rollers maintained in yieldable contact and between which the cable is fed; high speed drive means including a prime mover and transmission for communicating power to the rollers; a cable supply reel; a brake for the reel; means for normally holding the brake in braking contact with said reel; and means for supporting the cable and coacting with the brake and the cable to release the brake in response to the force of projection of said cable, said means for normally holding the brake in braking contact causing the brake to resume its braking action as the force of projection is expended; and a dashpot cooperating with said last-named means and with the brake to effect a uniform and smooth operation of the mechanism.

6. A mechanism for projecting wire cable to a distance comprising a system of rollers, including means for maintaining said rollers in friction contact and under yielding tension; a sectional frame assembly, a first section of said assembly supporting said rollers and being adjustable angularly in a vertical plane, and another section carrying the first section and being adjustable in azimuth; means for locking the first named section in different angular positions to determine the trajectory of the cable during the projecting operation; a source of power; a system of gearing comprising a first gear wheel carried by said sectional frame assembly and operatively connected to one of said rollers, and a second gear wheel engaging the first gear wheel driven by said source of power and positioned to be operable to drive the first gear wheel irrespective of the adjustments of the first and second sections in their respective planes; and means for locking the second named section in any position throughout its range of adjustment in azimuth.

7. A mechanism for projecting cable to a distance comprising a system of driven rollers and a drive roller; a frame assembly comprising sectional components, one of said components having the driven rollers mounted therein; a shaft on which the drive roller is keyed and bearings in which said shaft is journaled; means for angularly changing the position of the first named component pivotally about said shaft as an axis to determine the angle of projection; means cooperating with said components for locking said first-named component in different adjusted positions; said first-named component including means permitting opening and closing the said first-named component to permit operative adjustments; a prime mover; and a flexible transmission operatively coupling the prime mover with the drive roller.

8. A mechanism for projecting wire cable to a distance comprising a system of rollers, including driven rollers between which the cable is fed; tensioning means for maintaining said driven rollers in yieldable contact; a system of gearing for driving the rollers; a frame assembly com-

prising sectional components, one of said components having the roller system mounted therein and being angularly adjustable in a vertical plane, and another of said components having elements of the gearing system mounted therein and being adjustable in azimuth; means for locking the first-named component in different angular positions to determine the trajectory of the projected cable; means for locking the second-named component in any position throughout its range of adjustment in azimuth to determine direction in a horizontal plane; a prime mover; and means for operatively connecting the gearing system therewith.

9. A mechanism for projecting cable and the like to a distance comprising a drive and a pair of driven rollers; a sectional frame assembly in which said rollers are mounted as an operative group, one section of said frame being adjustable in different angular positions to change the angular position of said driven rollers and to control the trajectory of the cable; bearings for the rollers and tensioning means operative with the bearings for maintaining the rollers with their peripheral surfaces in yieldable contact; means to permit adjustment of another section of the frame in azimuth to control projection angle in a horizontal plane; and including means for locking the last-named section in any position throughout its range of adjustment; a prime mover; and means for operatively connecting the drive system therewith to perform the function of projection.

10. In a mechanism for projecting cable and the like to a distance, a system of projection rollers having their peripheral surfaces normally held in yieldable frictional contact and one of said rollers functioning as a drive roller; a drive shaft on which said last-named roller is keyed; a sectional framework in one section of which said rollers are operatively mounted, said section being movable about said shaft as an axis to control the trajectory angle of the said rollers; means for rotating said section to vary the trajectory angle; a turret on which the framework is supported and about which the framework is rotatable in azimuth; means for locking the framework in adjusted positions on said turret; and means for operating said last-named means, said means including a lever which also functions to manipulate the framework in rotational movement.

11. A mechanism for projecting cable and the like to a distance comprising a support and a system of projection rollers mounted on the support, said rollers being maintained in yieldable frictional contact and between which the cable is fed; high speed drive means including a prime mover and a flexible transmission for transmitting drive to the rollers; a cable supply reel mounted on said support; means for controlling the reel including a brake for the reel; means for yieldably holding the brake in braking contact with said reel; means co-acting with the brake and cable to operate the brake in response to cable tension, said means including an arm pivoted for movement in a vertical plane centrally of said reel, a carrier wheel for engaging the cable swivelled on said arm, and a tubular element carried by said arm and acting to center and guide the cable over the carrier wheel; and said means including a crank connected with said arm and slidably connecting said brake to release the brake when the cable is tensioned.

12. A mechanism for projecting cable to a dis-

tance comprising a support and a system of projection rollers mounted on the support, said rollers being maintained in yieldable frictional contact and between which the cable is fed; a cable supply reel; means for controlling the reel including a brake for the reel; means for yieldably holding the brake in braking contact with said reel; means co-acting with the brake and cable to operate the brake in response to tension applied to the cable, said means including an arm pivoted for movement in a plane centrally of said reel, a grooved carrier wheel for engaging the cable swivelled on said arm, and a tubular element attached to said arm acting to center and guide the cable in its travel over the carrier wheel; auxiliary guide rollers, including an intermediate guide element interposed between said carrier wheel and projection rollers to maintain the cable in proper feeding position in relation to said last named rollers; and said means including a crank connected with said arm and slidably connecting said brake to release the brake when the cable is tensioned.

13. A mechanism for projecting cable to a distance comprising a support and a system of projection rollers mounted on the support, said rollers being maintained in yieldable frictional contact and between which the cable is fed; a cable supply reel; means for controlling the reel including a brake for the reel; means for yieldably holding the brake in braking contact with said reel; means co-acting with the brake and cable to operate the brake in response to tension applied to the cable, said means including an arm pivoted for movement in a vertical plane centrally of said reel, a grooved carrier wheel for engaging the cable swivelled on said arm, and a tubular element attached to said arm acting to center and guide the cable in its travel over the carrier wheel, said element being provided with means to permit removal of the cable; auxiliary guide rollers, including an intermediate guide element to maintain the cable in proper feeding position in relation to said last-named rollers, said element being formed as a two-part structure and provided with means to permit removal of the cable without cutting; and said means including a crank connected with said arm and slidably connecting said brake to release the brake when the cable is tensioned.

14. The method of laying field wire at the side of the path of movement of a moving vehicle which includes projecting, from the vehicle linearly along the axis of the wire, the field wire at such rate that a greater length of wire is projected in a given time than the distance traveled by the vehicle during such time, at such high speed at an angle above the horizontal plane as to thereby effect a long trajectory above such plane, at an angle in said horizontal plane with the path of movement of the vehicle whereby the wire is thrown to the side of the path of movement of the vehicle; and varying the horizontal and vertical angles of projection to thereby throw the wire to desired places at the side of the path of movement of the vehicle.

15. A projector for cable and the like comprising a system of drive and driven rollers; means for maintaining the rollers in operative contact under spring tension; a frame assembly in which said rollers are mounted; means for moving the frame assembly to determine the direction for projecting the cable in a horizontal plane; means to control the trajectory of the cable; a reel for the cable; and means for controlling the cable projecting operation comprising a carrier ele-

ment responsive to the tension effected in the cable by the operation of said rollers, and braking means responsive to and controlled by said carrier element for effecting a braking action on the reel when the tension in said cable due to action of the rollers is small.

16. A cable projector of the class described comprising a system of drive and driven rollers; a frame assembly in which said rollers are operatively mounted; means for maintaining the rollers in yielding contact under spring tension; means for opening and closing said frame to permit adjustment and removal of the rollers; means to effect angular adjustment of the frame assembly to control the angle of projection of the cable in a horizontal plane; means to control the trajectory of the cable in the vertical plane; a cable supply reel; control means for determining the degree of tension in the cable as it leaves said reel comprising means which has a portion biased against the cable, and which moves to a position determined by the tension in the cable; and brake means operated by changes in position of said control means for effecting a braking action on said reel when the control means is in a position which indicates the tension in the cable is small and for reducing the effectiveness of the braking action on said reel when the control means changes its position to indicate that tension in said cable is increasing.

17. A mechanism for projecting cable or the like to a distance, comprising a system of rollers, including driven rollers between which the cable is fed; tensioning means for maintaining said driven rollers in yieldable contact; a frame assembly in which said rollers are mounted, said frame assembly comprising a component supporting said driven rollers, and adjustable angularly in a vertical plane to permit control of the angle of projection of the cable; a prime mover; a drive system for the rollers and means for operatively coupling the same to said prime mover; a cable supply reel; means for controlling the cable projecting operation, comprising a braking device normally acting to exert a braking force upon said reel; and means including a carrier element for supporting the cable and coacting with the

brake and with said cable and responsive to tension of the cable to release the brake; and means to restore said brake to normal braking position upon the reel as the wire from the reel slackens.

- 5 18. A mechanism for projecting cable or the like to a distance comprising a system of rollers, including driven rollers between which the cable is fed; tensioning means for maintaining said driven rollers in yieldable contact; a frame assembly in which said rollers are mounted, said frame comprising a component supporting said driven rollers and adjustable angularly in a vertical plane to permit control of the angle of projection of the cable; a prime mover; a drive system for the rollers, and means for operatively coupling the same to said prime mover; a cable supply reel; means for controlling the reel comprising a brake and including a spring element for normally holding the brake in braking contact with the said reel; means coacting with the brake and cable to operate the brake in response to cable tension, said means including a movable arm, a carrier wheel for engaging the cable swivelled on said arm, and said means including a crank cooperating with said arm and brake to release the brake when the cable is tensioned.
- 10 19. A mechanism for projecting cable to a distance comprising a system of rollers, including driven rollers between which the cable is fed for projection; tensioning means for maintaining the rollers in yieldable contact; a frame assembly in which said rollers are operatively mounted; a prime mover; a drive for the rollers and means for operatively coupling the drive to said prime mover; a cable supply reel; means to control the reel comprising a brake and including a spring element for normally holding the brake in braking contact with the said reel; means coacting with the brake and cable to operate the brake in response to cable tension, said means including a movable arm, a carrier wheel for engaging the cable swivelled on said arm, and said means including a crank cooperating with said arm and brake to release the brake when the cable is tensioned.
